US00D946546S

(12) **United States Design Patent** (10) Patent No.: **US D946,546 S**
(45) Date of Patent: **** Mar. 22, 2022**

(54) **ELECTRONIC DEVICE**

- (71) Applicant: **Samsung Electronics Co., Ltd.**, Suwon-si (KR)
- (72) Inventors: **Ji Young Lee**, Seoul (KR); **Hyok Su Choi**, Seoul (KR); **Hong Ku Yeo**, Seongnam-si (KR); **Min Hyouk Lee**, Seoul (KR)
- (73) Assignee: **SAMSUNG ELECTRONICS CO., LTD.**, Suwon-si (KR)
- (**) Term: **15 Years**
- (21) Appl. No.: **29/683,782**
- (22) Filed: **Mar. 15, 2019**

Related U.S. Application Data

- (63) Continuation of application No. 29/538,467, filed on Sep. 3, 2015, now Pat. No. Des. 848,387, which is a continuation of application No. 29/521,984, filed on Mar. 26, 2015, now Pat. No. Des. 784,279.

(30) **Foreign Application Priority Data**

CLAIM

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a rear perspective view thereof.

The broken lines in the figures illustrate portions of the electronic device which form no part of the claimed design.

1 Claim, 6 Drawing Sheets
